UNITED STATES PATENT OFFICE.

ALBERT H. BRIGHAM, OF WHITMAN, MASSACHUSETTS.

APPARATUS FOR HEADING NAILS OR TACKS.

SPECIFICATION forming part of Letters Patent No. 722,669, dated March 17, 1903.

Application filed August 25, 1902. Serial No. 120,877. (No model.)

To all whom it may concern:

Be it known that I, ALBERT H. BRIGHAM, a citizen of the United States, residing at Whitman, county of Plymouth, State of Massachusetts, have invented an Improvement in Apparatus for Heading Nails or Tacks, of which the following description, in connection with the accompanying drawings, is a specification, like characters on the drawings representing like parts.

In United States Patent No. 658,203 granted to me September 18, 1900, I have shown an apparatus for heading nails or tacks wherein the die provided with a head-forming opening is supported and guided in a die-carrier in such manner that a highly-effective apparatus is secured and adaptable to a wide range of work. My present invention relates to apparatus of like character; and it has for its object the production of novel means for holding and guiding the die in the die-carrier.

The various novel features of my invention in its present embodiment will be hereinafter described, and particularly pointed out in the following claims.

Figure 1 is a longitudinal sectional view of a portion of a nail or tack making machine with one form of my invention embodied therein. Fig. 2 is a similar view, but showing the die in position to effect the heading of the nail or tack, the die-carrier being broken off. Fig. 3 is a front elevation of the die-carrier, die, and guide-plate therefor. Fig. 4 is a side elevation of the die proper, and Fig. 5 is a view similar to Fig. 1 of the die-carrier detached and a modified form of die.

The coöperating dies *a* *b*, Figs. 1 and 2, to receive and grip between them the blank *d* and having suitable seats or depressions *a'* *b'*, Fig. 1, to shape and form the under side of the head *d'* of the blank, are of usual construction.

The heading-die comprises a shank or die carrier *c*, having a central longitudinal bore *c'*, enlarged and screw-threaded at its rear end at *c''*, Fig. 1, and counterbored at its front end, as at *c'*, substantially as in my patent referred to, the bore receiving the heading-pin *c*, which is longitudinally adjusted by a threaded rod *c*, screwed into the threaded end of the bore, the said rod *c* also taking

up end thrust of the heading-pin. In my present invention I have chambered the front end of the die-carrier at *c'* concentric with the counterbore *c'*, and this chamber is closed by a guide-plate *g*, rigidly secured to the die-carrier by screws *s* and having a circular aperture *g* opposite the end of the holder *c*. This holder for the heading-pin *c* is shown as a removable tubular bushing, preferably split longitudinally at *c*, (see Figs. 1 and 5,) seated in the counterbore *c'* and projecting into the chamber *c'*, the inner end of the holder resting firmly upon the shoulder *s*, substantially as in my patent. The die proper is shown herein as a plug *f*, usually of hardened steel and preferably cylindrical in cross-section and fitted to freely slide longitudinally in the aperture *g* of the plate *g*, the die having at its inner end an annular retaining-flange *f*. A coiled spring *s*, shown as surrounding the projecting end of the holder *c*, is interposed between the bottom of the chamber *c'* and the inner end of the die; and, as shown in Fig. 1, the spring normally holds the die projected through the guide-plate, the flange *f* limiting such movement of the die. The die is provided with a head-forming opening *f'*, shown as a central hole of sufficient diameter to receive the end of the heading-pin *c*, which projects beyond the end of the holder *c* and enters the hole in the die. One or more set-screws *s*, extended into the die-carrier *c*, bear upon the holder *c* to clamp it upon the heading-pin, as in Fig. 3. I prefer to slightly round off or convex the outer end of the die peripherally, as at *f*, so that its central portion shall firmly bear upon the dies *a* and *b* during the heading operation.

In the present instance of my invention the upper part of the head *d'* of the nail or tack is cylindrical and forms the base of a cone, and the heading-pin is so adjusted that when the heading is effected the cylindrical part of the head will be formed in the head-forming opening of the die, the outer end of the heading-pin determining the thickness of such cylindrical part of the head of the nail or tack, while the conical part of the head is formed by the dies *a* and *b*. The distance between the inner end of the die *f* and the adjacent end of the holder *c* may, if desired, be such that when the heading-pin closes the

head-forming opening, as described, the die will bottom upon and be supported by the holder. This is not necessary, however, as the spring s^x , which projects the die, can 5 readily be made strong enough to give any necessary support to the die during the heading operation.

In Fig. 1 the dies a and b are holding the blank, and the end thereof which is to be 10 upset to form the head will enter the head-forming opening f' when the heading-die is moved forward into the position shown in Fig. 1, the die f being stopped by engagement with the dies a and b . The shank or 15 die-carrier c then continues its forward movement and the spring s^x is compressed, the advancing heading-pin c^3 engaging the end of the blank, upsetting it into the head-forming opening and the shaping or forming re- 20 cesses $a' b'$ in the dies a and b , the upsetting being completed when the die f is pushed into the die-carrier into the position shown in Fig. 2. After forming the head on the blank the die-carrier c is withdrawn with the heading- 25 pin, the spring s^x maintaining the die f against the dies a and b until the retaining-flange f^x engages the guide-plate g . The latter is of sufficient thickness to accurately and positively guide the die and maintain it 30 properly centered, as the guide-plate is rigidly connected with the die-carrier. The chamber c^{12} provides space for the spring and for the retaining-flange of the die in its movements. By varying the longitudinal adjust- 35 ment of the heading-pin to regulate the effective depth of the head-forming opening in the die, a greater or less amount of metal may be upset, according to the size and shape of the head to be formed upon the blank. A 40 check-screw c^8 is shown in Fig. 1 inserted in the threaded portion c^6 of the bore of the die-carrier and engaging the end of the rod c^5 to securely lock the latter in position when adjusted.

45 A modified form of die is shown in Fig. 5, the die h being therein shown as having a recess h^5 in its inner end, coaxial with the hole h' , which receives the heading-pin, said recess being of a diameter to easily receive 50 the projecting end of the holder c^x when the spring s^x is compressed. In this construction the holder serves to assist in guiding the die in its longitudinal movement during the heading operation, the apparatus in other 55 respects being the same as hereinbefore described, the die having a retaining-flange h^x on its inner end.

Having described my invention, what I claim as new, and desire to secure by Letters 60 Patent, is—

1. In a heading-die, a die-carrier chambered at one end and having a central, longitudinal bore, a tubular holder within the chamber and coaxial with the bore, a guide-plate rigidly 65 secured to the chambered end of the die-carrier and having a die-receiving aperture, a yieldingly-supported die longitudinally mov-

able in said aperture, and guided by the plate, and having a head-forming opening, a heading-pin extended through the holder into the die, and means to secure the heading-pin in 70 the die-carrier.

2. In a heading-die, a die-carrier chambered at one end and having a central, longitudinal bore, a tubular holder within the chamber and coaxial with the bore, a guide-plate rigidly 75 secured to the chambered end of the die-carrier and having an aperture opposite the holder, a die longitudinally movable in said aperture, and having a retaining-flange at its inner end, said die having a head-forming opening, a heading-pin extended through the holder into the die, and means to secure the heading-pin in position.

3. In a heading-die, a die-carrier chambered 85 at one end and having a central, longitudinal bore, a tubular holder within the chamber and coaxial with the bore, a guide-plate rigidly secured to the chambered end of the die-carrier and having a die-receiving aperture, a 90 die longitudinally movable in said aperture, and having a retaining-flange at its inner end, said die having a head-forming opening, a spring interposed between the bottom of the chamber and the die, to project the latter, a 95 heading-pin extended through the holder into the die, and means to secure the heading-pin in the die-carrier.

4. In a heading-die, a die-carrier having a central longitudinal bore, a removable tubular 100 holder seated in the carrier and coaxial with the bore, a guide-plate rigidly secured to the end of the die-carrier beyond the holder and having an aperture opposite the end of the latter, a spring-controlled die longitudinally 105 movable in said aperture and having a retaining-flange at its inner end, said die having a head-forming opening, a heading-pin inserted in the holder and extended into the die, and means to retain the heading-pin in 110 said holder, the die when in operation being supported and guided by the guide-plate.

5. In a heading-die, a die-carrier chambered at one end and having a central, longitudinal bore, counterbored at the end adjacent the 115 chamber, a removable, tubular holder seated in the counterbore and projecting into the chamber, a guide-plate closing the chamber and rigidly secured to the die-carrier and having an aperture opposite the holder, a die 120 longitudinally movable in the aperture of and guided by said plate, said die having a head-forming opening, and a retaining-flange at its inner end, a controlling-spring surrounding the holder and interposed between the 125 bottom of the chamber and the inner end of the die, a heading-pin extended through the holder into the die, and means to secure the heading-pin in said holder and die-carrier, the die when in operation compressing the 130 spring.

6. In a heading-die, a die-carrier chambered at one end and having a central, longitudinal bore, a removable, tubular holder, seated in

the front end of the bore and projecting into the chamber, a centrally-apertured guide-plate closing the chamber and rigidly secured to the die-carrier, a spring-controlled die longitudinally movable in the guide-plate and having a head-forming opening, and a retaining-flange at its inner end, a heading-pin extended through the holder into the die, and means to retain the heading-pin in fixed position.

7. In a heading-die, a die-carrier chambered at one end and having a central, longitudinal bore, a tubular holder seated in the adjacent end of and coaxial with the bore and projecting into the chamber, a guide-plate closing the chamber and having an aperture opposite the holder, a spring-controlled die longitudinally movable in the aperture and having a retaining-flange at its inner end, a heading-pin inserted in the holder, and means to retain said heading-pin therein, the projecting end of the holder entering the recessed end of and preventing lateral movement of the die when the latter is moved inward.

gitudinally movable in the aperture and having a retaining-flange at its inner end, said die having a head-forming opening and a recess in its inner end, a heading-pin inserted in the holder, and means to retain said heading-pin therein, the projecting end of the holder entering the recessed end of and preventing lateral movement of the die when the latter is moved inward.

In testimony whereof I have signed my name to this specification in the presence of two subscribing witnesses.

ALBERT H. BRIGHAM.
